(57) **CLAIM**

The ornamental design for an infusion device button, as shown and described.

DESCRIPTION

FIG. 1 is a perspective view of an embodiment of an infusion device button showing our new design;

FIG. 2 is a top view of the infusion device button shown in FIG. 1;

FIG. 3 is a left side elevational view of the infusion device button shown in FIG. 1;

FIG. 4 is a front elevational view of the infusion device button shown in FIG. 1;

FIG. 5 is a rear elevational view of the infusion device shown in FIG. 1;

FIG. 6 is a right side elevational view of the infusion device button shown in FIG. 1; and,

FIG. 7 is a bottom view of the infusion device button shown in FIG. 1.

Broken lines in the drawing figures represent unclaimed environmental structure, are for illustrative purposes only, and form no part of the claimed design.
